UNITED STATES PATENT OFFICE.

THEODORE CARTER, OF VALLEY STREAM, NEW YORK.

VAMP EASER.

Application filed September 16, 1927. Serial No. 219,862.

This invention relates to means for stretching the vamp throat of a shoe to adjust it to the individual instep.

An object of the invention is to provide 5 an adjustable tool for stretching only the throat of the vamp of a shoe without otherwise altering the size or symmetrical appearance of the vamp, the tool being so flexible in its operation that its parts 10 properly adjust themselves whether the shoe is high heeled or low heeled and whether it is a heavy oxford or light dancing pump.

The invention is particularly adapted for stretching the vamp throat of pumps which 15 comprise a large percentage of all women's shoes. These shoes are made on various patterns such as opera pumps, which employ no fasteners to hold them on the foot, and strap pumps which are held on the foot by 20 means of straps passing over the instep and fastened by means of buttons, buckles or other fastening devices.

In wearing shoes of this type the edge of 25 the vamp is forced by the foot from its original line and often tends to press on the foot, thereby subjecting the wearer to much discomfort. This condition is due partly to the improper design and measurement of 30 shoes and partly to the marked dissimilarity in feet which must be fitted with shoes of standard sizes. Some feet are fleshy while others are thin, and in the bony formation some insteps rise abruptly while others recede from the lines of the shoe pattern.

35 Heretofore, attempts have been made to relieve the tension at the vamp throat by using shoe stretchers such as are commonly employed to stretch shoes across the ball region of the vamp. These tools are unsuited for this work because they enlarge 40 the entire vamp and change the shape and symmetry of the shoe before any appreciable stretching is noticed at the vamp throat. As a last resort, shoe dealers sometimes alter 45 the line of the vamp by cutting and rebinding, which at best gives the appearance of a repair job.

The present invention provides a simple 50 and efficient tool for easing the pressure at the vamp throat of a shoe without otherwise stretching it. This tool includes a heel piece inserted in the heel seat and a tilting easer block inserted under the vamp throat. The block is relieved so as not to stretch 55 the ball region of the vamp but is rounded to conform generally to the contour of the

vamp throat. When the block moves forward and tilts upon the application of power, only the vamp throat is stretched. Sliding and tilting of the block in the desired manner is facilitated by rounding it on the bottom, and by providing a flat filler piece on which it can slide and tilt when the power is applied. The easer block is separated from the heel piece by a suitable power 60 device such as a screw.

A feature of the invention resides in providing a universal or ball and socket connection between the heel piece and the easer block to not only facilitate the forward sliding and tilting movement of the easer block when power is applied, but also to allow relative lateral movement between the block and the heel piece to fit shoes of different shapes, and relative vertical movement to fit 70 high and low heeled shoes. In the preferred form shown herein, the power screw is pivotally connected as by a ball and socket to one of the elements, such as the heel piece, and carries a threaded nut having a lug 75 which is horizontally pivoted to the other element, such as the easer block.

In a modified form, the screw is directly between the elements, one carrying a nut engaging the screw, and the other a ball 80 recess in which the rounded end of the screw can pivot when power is applied. This latter form embodies the broad principle of the invention but is not as flexible in accommodating itself to various types of shoes, as 85 in the preferred form.

The invention will be described in detail in connection with the accompanying drawings, in which,

Fig. 1 is a longitudinal vertical section 90 through a high heeled shoe showing the tool in position.

Fig. 2 is a similar view through a low heeled shoe showing the tool in position.

Fig. 3 is a similar view through a shoe 100 showing a modified form of the tool in position.

Fig. 4 is a perspective view of the preferred form of tool.

Fig. 5 is a plan view of the preferred 105 form.

In the drawings the tool is shown in its preferred form in Figs. 1 and 2 and comprises an easer block 1, a heel piece 2, and a smooth filler piece 3 shaped like a half sole. 110 These parts may be made of wood or any other suitable material. The easer block 1

has a sloping front surface 4 (see Fig. 4) which projects above the vamp throat 5 and recedes sharply in the direction of the ball region of the vamp. The sloping front surface 4 is transversely rounded to conform substantially to the contour of the vamp throat. The under surface of the block 1 is preferably curved or rounded in the manner shown to provide a rocking base portion 6. The heel piece 2 comprises a narrow elongated block which is freely insertible in the shoe against the bottom of the counter and lying on the heel seat, and is provided with a rounded end 7, adapted to rest against the counter 8, as shown. The sides of the heel piece 2 are cut away or shaped as at 9 to prevent contact of these portions with the flexible sides of the counter. The preferred adjustable power mechanism, which is operated to separate the block 1 from the heel piece 2, is a screw member 10, one end of which is provided with a handle 11 and the other end of which is provided with a ball element 12. This ball element is adapted to be seated in a recess in the front face of the heel piece, the end of this recess being closed by a slotted plate 13 through the slot in which a reduced portion 14 of the screw extends. This ball and socket connection between the screw and the heel piece permits the heel piece to move in a plurality of planes with respect to the screw and to the easer block 1. The screw is also provided with a threaded nut 15 which has a dependent lug 16, the end of which extends into a recess 17 in the rear face of the easer block and pivoted to the easer block in said recess by means of a horizontally disposed pin 18. This connection between the lug and the easer block permits pivotal motion of the easer block in a vertical plane with respect to the lug and provides relative movement between the easer block and the screw and the heel piece. It will be noted that the connection of the ball and socket joint to the heel piece is made near the bottom of the front face bringing the line of thrust through the heel piece and the screw in line with the bottom of the counter where the heel piece bears thereagainst. It will also be noted that the connection of the screw to the easer block 1 through the lug 16 is at a point to the rear of the easer block well above the curved base portion 6 of the easer block and consequently any thrust transmitted to the easer block through the lug 16 will tend to tilt it forward and in so doing bring the curved upper surface of the block into contact with the vamp throat 5 to stretch the same.

The filler piece 3 provides a smooth surface on which the easer block can be slid forward under the action of the screw and can freely tilt or rock thereon to perform its function. It will also be observed that

by reason of the flexibility of the connections between the screw, the easer block, and the heel piece, these parts will automatically adjust themselves in the proper position in any type of shoe whether it be a right or left shoe or a high heeled or low heeled one. In Fig. 1 the fact that the heel piece is higher than the easer block will cause the easer block to assume a position in which it is tilted forward more than it will in a low heeled shoe, as shown in Fig. 2.

In a modified form of the invention shown in Fig. 3, the heel piece is inserted as before in the shoe, but in this form the adjusting mechanism comprises an elongated screw 19, having a threaded end which extends through a nut 20 in the front face of the heel piece 2 and freely enters a chamber 21 which extends longitudinally through the center of the heel piece. The forward end of the screw 19 terminates in a blunt rounded head 22, which is loosely received by a socket member 23 disposed in a recess in the rear face of the easer block 1. The screw 19 is adjusted by means of an integral thumb piece 24. The section lines $a-a$ in Figs. 1, 2 and 3 indicate the general direction of the thrust between the base of the counter and the vamp throat for the different types of shoes.

In using the tool to stretch the vamp throat of a shoe the filler piece 3 is placed inside the forepart of a shoe, as shown in the drawing. The easer block is then inserted under the vamp throat with the rounded base portion resting on the smooth upper surface of the filler piece 3. The heel piece 2 is then placed on the heel seat of the shoe with its rounded rear end resting snugly against the bottom of the counter 8. In the form shown in Figs. 1 and 2, the handle 11 is operated to force the easer block forward. In the modified form shown in Fig. 3 the thumb piece 24 is operated to effect this result. The base of the counter 8 at the heel seat of the sole is very stiff and unyielding in its construction and hence when pressure is exerted thereagainst by the action of the screw, this portion does not yield and consequently the easer block is forced forward against the vamp throat which must yield. As the screw is turned in the proper direction the easer block is moved forward and its top surface is thrust upwardly due to the forward tilting or rocking movement of the block as it slides forward on the filler piece 3. The rounded sloping upper surface of the easer block is thus wedged underneath the vamp throat and stretches it uniformly without distorting the ball region of the shoe since no pressure is exerted on any other flexible portion of the vamp there is no tendency towards distortion. The filler piece also firmly holds the outer sole of the shoe down as the easer block is moved forward.

ward and thus prevents crushing and wrinkling of the vamp material during operation.

This application is a continuation in part, of my co-pending application entitled Vamp 5 easer, filed April 27, 1927, S. N. 186,974.

I claim:

1. A vamp easer comprising a heel piece, a forwardly tilting easer member formed to engage only the vamp throat, and interposed means for separating the heel piece and the easer block, said heel piece and easer block being relatively vertically and laterally movable during the application of power.
- 10 2. A vamp easer comprising a heel piece, a sliding and forwardly tilting easer block formed to engage only the vamp throat, and interposed means for separating the heel piece and the easer block, said means being 20 flexibly connected to the easer block and heel piece to permit them to have relative vertical and lateral movement during the application of power.
- 15 3. A vamp easer comprising a heel piece, a sliding and forwardly tilting easer block formed to engage only the vamp throat, and interposed means for separating the heel piece and the easer block, said means being 25 flexibly connected to the easer block and the heel piece, one of the connections permitting relative movement in one plane and the other connection permitting relative movement in a plurality of planes.
- 30 4. A vamp easer comprising a heel piece, a sliding and forwardly tilting easer block formed to engage only the vamp throat, a filler piece disposed beneath the easer block to provide a smooth surface on which the block may slide and tilt, and interposed 35 means for separating the heel piece and said block.
- 35 5. A vamp easer comprising a heel piece, a sliding and forwardly tilting easer block formed to engage only the vamp throat, a filler piece disposed beneath the easer block to provide a smooth surface on which the block may slide and tilt, and interposed 40 means for separating the heel piece and the easer block, said heel piece and block being relatively vertically and laterally movable 45 during the application of power.
- 45 6. A vamp easer comprising a sliding and forwardly tilting easer block formed to engage only the throat of the vamp, the base 50 of said block being rounded to permit it to tilt freely as it is moved forward, and a filler piece disposed beneath the block to provide a smooth surface on which the block may slide and tilt freely as it is moved 55 forward.
- 60 7. A vamp easer comprising a heel piece,

a sliding and forwardly tilting easer block formed to engage only the throat of the vamp, means for separating the heel piece and easer block, said means connected to the easer block on a horizontal pivot and to the heel piece by a ball and socket joint.

65 8. A vamp easer comprising a heel piece, a sliding and forwardly tilting easer block formed to engage only the throat of the vamp, a screw connected to the heel piece by a ball and socket joint, and to the easer block on a horizontal pivot, and a filler piece disposed beneath the easer block to permit the block to tilt freely as it is moved forward.

70 9. A vamp easer comprising a heel piece formed to engage the counter of a shoe only at the bottom thereof to the rear of the heel, a sliding and forwardly tilting easer block 75 formed to engage only the throat of the vamp, a screw connected to the heel piece by a ball and socket joint, and to the easer block on a horizontal pivot, and a filler piece disposed beneath the easer block to permit the block to tilt freely as it is moved forward.

80 10. A vamp easer for pumps comprising a heel piece, a forwardly tilttable easer member having its upper surface formed to engage only that part of the upper covering the instep of the foot, and means interposed between the heel piece and the easer member for separating them to forwardly tilt the easer member.

85 11. A vamp easer comprising a heel piece, a sliding and forwardly tilting easer block having its upper surface formed to engage only that part of the shoe upper covering the instep of the foot, the bottom of said block being rounded to permit it to tilt freely as it is moved forward, and means interposed between the heel piece and the easer block for separating them to move the easer member forward.

90 12. A shoe easer comprising a heel piece having a socket in its forward lower portion, a forwardly and upwardly extending screw having a head loosely fitting in said socket for limited universal movement, an actuating handle on the forward end of the screw, a nut on the intermediate portion of the screw having a downwardly and forwardly extending lug, and an easer block horizontally pivoted to the forward end of said lug for limited vertical pivotal movement.

100 Signed at 205 Cochran Place, Valley Stream, in the county of Nassau, and State of New York, this fourteenth day of September, A. D. 1927.

THEODORE CARTER.
